UNITED STATES PATENT OFFICE.

JOHN W. SLATER, OF SLATERSVILLE, RHODE ISLAND.

MEANS FOR REVERSING AND CONTROLLING INTERNAL-COMBUSTION ENGINES.

No. 828,064.

Specification of Letters Patent. Patented Aug. 7, 1906.

Application filed May 28, 1905. Serial No. 261,869.

To all whom it may concern:

Be it known that I, JOHN W. SLATER, a citizen of the United States, residing at Slatersville, in the county of Providence and State of Rhode Island, have invented a new and useful Improvement in Means for Reversing and Controlling Internal-Combustion Engines, of which the following is a specification.

This invention relates to means for reversing and controlling internal-combustion engines; and its objects, which are threefold, may be summarized as follows: first, the provision of means actuated by the usual hand-lever whereby the usual inlet and exhaust valves may be respectively opened and closed in manner to permit the crank-shaft to drive either in the forward or reverse direction at the will of the operator; second, the provision of means actuated by the usual hand-lever enabling the usual inlet and exhaust valves to be regulated in their operation whether the crank-shaft be driving in the forward or reverse direction; third, the provision of means actuated by the usual hand-lever enabling the actuation of the usual ignition device at such periods that the firing of the charge is rendered effective for driving in either the forward or reverse direction.

In brief, my invention includes the following instrumentalities: a half-speed shaft carrying two cams oppositely arranged for the actuation of the inlet-valve through the medium of a bipart intermediate regulating member and two correspondingly-arranged cams for the actuation of the exhaust-valve. Where two or more cylinders are employed, each will be similarly equipped. Each pair of cams are designed so that when turning in one direction they will operate the push-rod or equivalent device for an inlet or exhaust valve to actuate it for the admission of combustible gases or exhaust to drive the crank-shaft in the forward direction and when turning in the opposite direction to operate said push-rod or the like to admit or exhaust the gases to drive the crank-shaft in the reverse direction. The bipart valve-actuating member is composed of two pivoted operating media for the push-rod of each valve, which media are oscillated in unison by the cams upon the half-speed shaft, the direction of movement imparted to the crank-shaft being determined through the timing of the oscillations of said media, which themselves are

governed by the direction of movement of said half-speed shaft.

In the drawings accompanying this application, Figure 1 is an elevation of parts embodying my improvements shown in operative relation with a valve of an internal-combustion engine. Fig. 2 is a detail plan view of the valve-operating media. Fig. 3 is a detail plan view of the cam-shaft and cams thereon; and Figs. 4 and 5, respectively, are perspective elevations of the two parts of which the valve-actuating member is composed.

In describing this invention I deem it unnecessary to illustrate a motor or the various parts thereof operating in conjunction with my improvements and have confined myself to the indication of a valve-opening having a valve, valve-stem, and push-rod, together with the direct intersecting parts constituting the mechanical elements through which I attain the results premised.

Thus the letter A may indicate a valve-opening of an internal-combustion cylinder; but whether it be intended as an inlet or exhaust is immaterial. Similarly, a indicates the valve seated in said opening, a' the valve-stem, and a² a push-rod adapted to reciprocate through a guide a³. The push-rod a² is provided with a pivotal extension a⁴; but throughout the specification these two parts will be referred to unitedly as the push-rod.

B indicates the hand-lever, which is fast upon a rock-shaft b, an arm, as b', which is also fast upon said shaft, extending therefrom and being connected with the push-rod through a pivotal link b².

C indicates a shaft which is driven, as at half-speed, from the crank-shaft of the motor. For the purpose of actuating a single valve this shaft C is equipped with a pair of oppositely-arranged cams, as c c'. Disposed intermediate the shaft C and the valve push-rod is a bipart actuating member, which communicates the cam action to the push-rod. This member consists of a pair of wings, as D D', having, respectively, the hubs d d', by which they are mounted in manner to oscillate upon a pivot or shaft, as d², collars, as d³ d³, serving to hold them in hinge-like relation. The upper edges of the wings D D' are conterminous and are arranged as or provided with ways, as d⁴ d⁴, each in form of a segment of a circle. The free end of the push-rod, which may be provided with a friction-wheel, as d⁵, abuts against and is

adapted to travel upon these ways as swung about its fulcrum through the manipulation of the hand-lever. The tailpieces, as $d^a d^b$, of the wings $D D'$ are disposed at opposite sides of the cam-shaft C , and said tailpieces, which may be provided with friction-rollers $d^a d^b$, are located, respectively, in the paths of the cams $c c'$. Said cams in their rotary action spread apart the tailpieces $d^a d^b$, correspondingly drawing together the ways $d^a d^b$. The wings $D D'$ are shown in their normal or inoperative position by solid lines and are represented in dotted lines as rocked by the cams $c c'$. The position of the push-rod upon either of the ways $d^a d^b$ determines the extent of the lift to be imparted to the valve, as is evident, such extent being less toward the central or neutral point above the pivot d^2 and increasing as the push-rod is moved out-wardly along a way d^1 .

Assuming the push-rod to be at a point intermediate the wings $D D'$ —namely, opposite their fulcrum or hinge—then their oscillatory action would not be communicated to the valves; but if said push-rod be swung over to one side—as indicated, for example, in Fig. 1—then the valve will be lifted once to every revolution of the cam-shaft, and this lift, as well as the ignition apparatus and the various steps of a gas-engine cycle, will be so timed that the explosion occurs when the crank-shaft is in position to receive the impulse—as, we will say, in the forward direction. It follows that if the push-rod be swung in the opposite direction the gas-engine cycle will become operative upon reversing the direction of the crank-shaft and cam-shaft, because the cams will then actuate the wings when the crank-shaft is in position to receive the impulse to rotate it in the reverse direction.

I am aware that just prior to moving the push-rod across the neutral point between the wings the ignition may be cut off, compression attained, and the ignition reinstated to fire the charge at such a time that it is concurrent with the proper cycle period, for either forward or reverse motion, whereby the momentum of the fly-wheel is overcome

and the operation of the engine reversed; but I have not considered it necessary to enlarge upon these details in this application, since they belong more particularly to the province of the engineer in assembling and adjusting the parts for a particular type of engine.

One important advantage attained through the use of my invention resides in the ability to throttle the engine, thereby controlling the inlet of gaseous mixture without interfering with the carburetor as set for the production of a suitable admixture. Another important advantage consists in the provision of the simple engine-reversing mechanism described, which obviates the necessity of employing the usual reversing-gears and simplifies the operation of applying the reverse.

Having now described my invention, I declare that what I claim is—

1. In an internal-combustion engine, a valve and a valve push-rod, a bipart actuator composed of two hinged members for said push-rod, a half-speed shaft having a pair of cams to oscillate said members, and means for subjecting the push-rod to the influence of either of said members, the oscillation of said members separately regulating the degree of lift of the valve and determining the direction of movement imparted to the crank-shaft and cams.

2. In an internal-combustion engine, a valve, a valve-stem, a push-rod therefor, means for swaying a portion of said push-rod in opposite directions from its vertical plane, and a valve-actuator comprising a pair of oppositely-hinged wings presenting unitedly a curved way for the free end of said push-rod, said wings having dependent tailpieces, together with a half-speed shaft bearing a pair of oppositely-disposed cams, situated between and adapted respectively to strike the respective tailpieces to thereby oscillate said wings.

JOHN W. SLATER.
